OSWEGO FALLS CORPORATION, OF FULTON, NEW YORK, A CORPORATION OF NEW
YORK.

CONTAINER-CLOSURE DISK AND THE PRODUCTION AND APPLICATION THEREOF.

Application filed March 28, 1926. Serial No. 97,677.

This invention relates to fibrous material hood cap disks that are rendered moldable on the heads of containers and self securing under said heads by the presence of a suitable binder carried by, at least the securing portions of, the annular skirts of such caps, and to the production and application thereof, and specifically the instant invention involves a group of such caps forming a multi-cap unit or package, as a new article of manufacture; and the objects and nature of the invention will be readily understood by those skilled in the art in the light of the following explanation of the method involved and of accompanying drawings that illustrate what we now believe to be the preferred mechanical expression or embodiment of our invention from among other forms and arrangements within the spirit and scope of the invention.

An object of the invention is to provide an exceedingly advantageous and economical block or package of binder-carrying hood cap disks and a method of producing the same and of applying disks therefrom.

Another object of the invention is to provide improvements in hood cap disks equipped with binder at the annular securing portions thereof and to produce and apply the same.

With this and other objects in view, the invention consists in a certain novel method and in structural features, arrangements, or combinations as more fully and particularly set forth and specified hereinafter.

Referring to the accompanying drawings, forming a part hereof:—

Fig. 1 is a view in side elevation of a group of loosely nested flexible sheet fibrous material flaring skirt hood cap disks before application of the binder thereto.

Fig. 2 is a side elevation of a stack of united hood cap disks forming a block or article of manufacture embodying the instant invention.

Fig. 3 shows a stack of united disks in longitudinal section, the spacing between the disks and the thickness or quantity of binder being exaggerated.

Fig. 4 shows in top plan a moldable cap separated from the group of Fig. 2.

Fig. 5 shows in side elevation, the cap molded and set on the container head.

The hood cap of Figs. 4 and 5 embodies a

paper or other sheet fibrous material disk having a circular flat imperforate center or top wall 1, and an annular drawn skirt or flange 2, an annular part of which skirt forms and constitutes the securing portion 2a, of the cap skirt that carries or embodies a suitable binder or plastic possessing the necessary characteristics to render the paper moldable and more or less soft when highly heated whereby the cap flange can then be molded against and to the head or mouth of the container covered by the cap, and capable of then setting to form securing the cap on and to the container head by reason of the set molded portion of the cap flange diametrically contracted under an exterior shoulder 70 of the container head.

The hood caps are made of any suitable flexible paper or fibrous material possessing the required strength and of the necessary grade or quality and thickness to meet trade requirements and particularly conditions encountered in distributing bottled milk. These caps are usually produced from sheet pulp board or paper by the use of drawing dies or punches.

The drawing die or punch machine operates on the flat sheet paper or stock which has usually been previously imprinted with the display matter to appear on the top of each hood cap. The machine cuts flat disks from the stock each usually bearing such display matter, and then draws or shapes such disks into approximate hood cap form, i. e. the central portion or top surrounded by a usually widely flaring annular flange 90 or skirt. In drawing the disk to form the flaring flange or long skirt, the surplus sheet material in the flange is taken up by an annular series of similar longitudinal folds, tucks or creases, each preferably V-shaped in cross section.

Our hood cap forming or drawing machine, discharges, the hood caps in one or more long advancing columns, made up of similar hood caps more or less tightly nested together with their flanges all projecting in the same direction and overlapping approximately throughout their lengths and usually with the creases or tucks of the flanges fitting within the creases or tucks of adjacent flanges, and with the cap tops or centers parallel and almost contacting.

As this column of nested flared disks or

caps advances, we take successive lengths thereof, and apply the binder composition while in hot liquid condition, to the exterior surfaces of the disk flanges that are exposed at the exterior of such length or that form the circumferential portion of such length. Each such length is in the form of an approximately solid elongated block, or in the form of a cylinder if the caps are drawn from circular disks, and is composed of a multiplicity of nested similar parallel flaring paper caps, any suitable number of such flared disks being included in such length, say from a few up to several hundred or more. The longitudinal circumferential surface of this block of closely nested flared disks, is formed by the exposed annular edge portions of the closely interfitting overlapping flaring portions or skirts of the disks, and it is an object of this invention to simultaneously apply to all of said flaring skirts of the block a sufficient quantity of the binder that will set to cement all of the disks together and to form a shell, sheathing or coating α , of binder covering and enclosing the longitudinal circumferential paper disk surface thereof, and furthermore to provide each disk, when subsequently separated from the block for application to a container, with sufficient binder to secure the cap on the container head, as herein set forth.

The liquid binder can be applied to the circumferential exterior surface of each block or group of flared disks in any desirable manner or by any suitable means.

The liquid binder can be applied to the block of nested disks by spraying, submerging, drenching or otherwise to enable the disks of the block to take up or absorb the desired quantity of binder, and when the binder sets and cools to form the enclosing exterior shell or coating and preferably layers or deposits of binder between the flanges of the disks that make up the block. If so desired, the exposed side faces of the end disks of the block can be protected from the liquid binder by caps or covers, before the block is subjected to the binder.

The blocks of nested disks can be rolled through the liquid binder, or can be otherwise carried through and completely submerged in the liquid binder, while the disks of each block are longitudinally held together to hold them nested to the desired extent.

Also, the blocks of nested disks, can be held in vertical position and exteriorly drenched by descending columns of the liquid binder, whether the blocks are arranged with the disk flanges extending upwardly or with their flanges depending. After the blocks have received the hot liquid binder, they are usually allowed to drain while subjected to a gradually decreasing high tem-

perature, and then are allowed to cool, whereupon the binder quickly sets, and the block of binder carrying disks is ready for packing and shipment. These blocks of secured binder carrying disks are prepared for sale to bottlers of milk and other products equipped with machinery for heating the blocks to a temperature above the softening or melting point of the binder so that the disks can be successively or one at a time separated from the block, and while still hot and moldable, placed in proper position on the container head, so that an appropriate molding and clamping head can annularly and diametrically mold the hot skirt flange thereto and contract the same under the exterior shoulder of the container head and thus hold the same until the flange cools and sets to rigid cap securing form.

When the block of nested disks is subjected to the liquid binder treatment, the exposed edge portion of the disks absorb and exteriorly take up a surplusage of binder which thereafter quickly sets thereon to form the block coating or shell, and also liquid binder penetrates short distances into the block between the contacting surfaces of the disks and thereafter sets therein cementing together the side faces of the disks near the circumferential edges thereof. However, we find that the air trapped between the disks serves to limit the penetration of the liquid binder into the block between the side surfaces of the disks, and thus prevent the presence of an undesirable binder surplus within the block.

We also find that the quantity of liquid binder taken up by the disks can be controlled to some extent by the temperature of the disks when they are subjected to the liquid binder bath. In other words, by pre-heating the paper disks we increase the proportion or quantity of liquid binder taken up by the disks, and thus can shorten the time of exposure of the disks to the binder bath. For instance, by preheating the paper disks so that their temperature will be about from 150° F. to 200° F. more or less, when subjected to the hot liquid binder bath, the disks will quickly absorb and carry the required quantity of binder for setting thereon and therein. The preheating operation presents hot paper disks to the liquid binder and enables the binder to more quickly penetrate the paper, and also expands the air in the block and increases the possibility of inflow of binder into the block between the disks.

We prefer to employ a hard high-melting point binder that is quick setting or cooling with good water resistant qualities, and is not objectionable for use on or in caps for capping milk bottles, or in establishments for bottling milk and other food products. We also use a binder that is an adhesive for

paper but that preferably will not form objectionable or fouling deposits on the surfaces of the containers and the securing heads.

- 5 Various binders are suitable for our purposes, whether or not such binders all fall within the meaning of the term plastic. Various natural and synthetic waxes, gums, resins, rosins, hardened metallic soaps, and 10 compositions thereof can be utilized as a binder for our purposes. For instance, we have among others successively employed a binder composed of carnauba and other hard high melting point quick setting waxes, and 15 various compositions of rosins, waxes and other substances.

It will be noted that each flared disk carries a coating of hard binder at the surrounding or circumferential edge portion 20 only, of its flaring flange, without regard to the impregnation of binder that may have entered into the body of the paper of the flange, and that this surrounding edge portion, constitutes the annular end portion of 25 the cap flange that is ultimately molded and contracted and that when set serves to secure the cap on the container head.

The binder coated block of nested caps, 30 may carry a surplus of binder at the exterior surfaces of the edges of the caps, but during the heating process at the bottlers, preparatory to the removal of the hot caps from the block one by one, while the binder is in effect liquefied so that the caps are not then cemented together, the binder is more or less uniformly distributed up and along the annular edge portion of each cap flange, by 35 the time the hot cap is on the container head ready for molding and setting thereon.

40 The block of binder carrying flared disks not only protects the inner surfaces of the flared disks from moisture, vermin, dust, dirt, and contamination during packing, shipment and handling, but also constitutes 45 a most convenient and economical package for shipment and handling, as well as an article that can be most economically produced, permitting the utilization of quantity production methods, avoiding the approximately prohibitive costs involved in separately handling each cap from the drawing machine to the container.

50 After the blocks of caps are separated from the columns fed from the cap forming and drawing machine, the blocks of caps are sterilized by the pre-heating operation and again by the temperature during the liquid binder bath, and after the binder has set to form the exterior shell, the caps are 55 protected from contact with the hands, except the end caps. However, the caps are again subjected to sterilizing temperature preparatory to application to the container heads.

The drawings, particularly referring to 65 Figs. 2 and 3, greatly exaggerate the usual thickness of the binder coating between the disks and at the exterior of the block, as well as the usual spacing between the disks of the stack. Also the edges of the disks of 70 the stack may not completely overlap throughout their lengths.

It is evident that various departures and variations might be resorted to without departing from the spirit and scope of our invention and hence we do not wish to limit our invention to substantially the exact disclosures hereof.

What we claim is:—

1. As a new article of manufacture, a 80 block composed of a stack of binder-carrying paper or like material caps for containers, and a binder material cementing said caps together and coating the longitudinal surface of the block. 85

2. As a new article of manufacture, a stack of binder-carrying nested flaring paper caps for containers and binder material securing said caps together to form a block.

3. As a new article of manufacture, a 90 stack of nested paper material hood caps, and binder material cementing said caps together, whereby each cap at its flange portion carries a portion of binder.

4. As a new article of manufacture, a 95 stack of binder-carrying paper material hood cap disks, provided with an exterior coating of binder applied directly to said disks.

5. As a new article of manufacture, a 100 block of nested paper material binder-carrying hood cap disks cemented together by the binder material of said disks, said material being located at the outer edge portions of 105 the disks and extending therebetween.

6. Several nested paper or like material flaring hood cap disks, and a hard quick-setting binder cementing said disks together and approximately coating the exposed circumferential edge portions thereof, whereby 110 said disks, when heated to liquefy the binder, can be separated one at a time for application and securing on container heads while hot and moldable.

7. A stack of nested flaring skirt flexible 115 fibrous material hood caps for container heads, and a hard binder for each cap skirt, said binder cementing the caps together and coating the circumference of the stack.

8. As a new article of manufacture, a 120 multi-cap unit, the exterior circumferential surfaces of which embody and are rendered stiff by a binder substance or composition, said unit consisting of a multiplicity of nested fibrous material hood caps. 125

9. In the production of binder-carrying sheet fibrous-material hood cap disks, that step which consists in subjecting the circum-

ferential edge portion of the hood cap disk to a hot liquid binder bath while the disk is in a preheated condition.

10. In the production of binder-carrying sheet fibrous-material flaring-skirt hood cap disks, those steps which consist in preheating the disks, then while hot subjecting the securing portions of the skirts to a bath of the binder while in a hot liquid condition, and then permitting the disks to cool and the binder to set on and in the securing portions of the skirts.

11. In the production of fibrous-material disks, for container hood capping purposes, that carry a hard quick-setting high melting point binder at their annular edge portions, those steps which consist in subjecting the annular edge portion only of a highly heated disk to the binder while in hot liquid form, whereby the liquid binder is absorbed thereby and adheres thereto, and then permitting the binder to set to hard condition therein and thereon, by cooling.

12. In the production of fibrous-material disks, for container hood capping purposes, that carry a hard high-melting point quick-setting binder; those steps which consist in subjecting at least the annular securing portion of the disk while highly heated to a high-melting point quick-setting normally-hard binder while in hot liquid condition, whereby liquid binder is absorbed by and adheres to the disk, and then permitting the disk to cool and the binder carried thereby to set to hard condition.

13. In the production of fibrous-material hood cap disks carrying a hard high melting point quick-setting binder; those steps which consist in holding together a multiplicity of said disks in stack form and while thus held flooding at least the longitudinal circumferential surface of the stack to the normally-hard binder while in hot liquid form, whereby the liquid binder adheres to and approximately covers said surface, and then permitting the liquid to cool and set to hard condition cementing the disks together and approximately coating said surface.

14. In the production of fibrous-material hood cap disks carrying a binder; those steps which consist in assembling a multiplicity of previously-formed fibrous material hood cap disks in stack form; heating the stack of disks; flooding the longitudinal exterior of the hot stack that is made up of the exposed annular edge portions of the disks with hot liquid binder, whereby the liquid binder enters between the disks distances approximately controlled by the air trapped between the disks; and cooling the stack and causing the binder within and on the longitudinal surface of the stack to set.

15. In the production of fibrous-material

flaring-skirt hood cap disks carrying a binder, those steps which consist in closely nesting a multiplicity of the fibrous-material flaring-skirt hood cap disks to form a stack; and cementing said disks of said stack together into block form by a longitudinal 70 coating of binder and layers of binder between the side faces of the annular edge portions of the disks.

16. Fibrous-material flaring-skirt hood cap disks carrying a hard quick-setting 75 binder, said disks closely nested together in stack form, and a hard quick-setting binder cementing said disks together and arranged between annular edge portions of the disks and coating the longitudinal surface of the 80 stack that is formed by the edge portions of the nested disks.

17. As an article of manufacture, a stack of fibrous material bottle closure disks cemented together and approximately circumferentially coated by a normally set plastic material that permits separation of the caps one by one from the stack for application to containers, when the stack is heated to 90 soften the plastic material.

18. In the production of a multi-cap block, as an article of manufacture, those steps which consist in forming a stack of separate paper material container closure disks, and then subjecting the stack as a 95 unit to a bath of plastic material liquefied by heat that on setting approximately coats the circumference of the stack and cements together the disks.

19. As an article of manufacture, a multiplicity of paper hood cap disks, for hood capping bottles, grouped together to form a stack and binder material set on the edge portions of the disks and securing together the disks of the stack, whereby the stack can 105 be heated to approximately liquefy the binder and permit separation of disks therefrom with each separated disk carrying binder for securing the same on a bottle head.

20. In the production of binder carrying hood cap disks for capping containers, those steps which comprise applying the binder in liquid form to the annular edge portions of a multiplicity of such disks assembled in 115 stack form, and then permitting the binder carried by the stack to set to secure the disks thereof together and provide each disk with a supply of binder for securing the same on a container head, when the disk 120 has been separated from the stack.

21. In the production and application of paper material hood caps carrying binder for securing the same on container heads, those steps which comprise securing together a stack of such hood caps by applying liquid binder to the stack in such quantity that each cap will carry binder for securing the 125

same; permitting the binder to set on the stack and caps whereby the stack can be thereafter handled as a unit; then treating said stack at the container hood capping situation to approximately liquefy the binder carried thereby; and while the stack is maintained with the binder in such condition, separating caps therefrom carrying the soft binder and applying the same to container heads for securing thereon by setting of the binder.

22. In the production and application of paper material hood cap disks carrying binder that when heated permits molding of the disks on container heads and securing thereof by setting of the binder; those steps which comprise depositing the binder in liquid form to a multiplicity of paper material hood cap disks arranged in stack form to secure the disks together in such form and provide each disk with binder, on setting of the binder; and then heating said stack to and maintaining the same at a temperature that will cause approximate fusing of the binder and distribution thereof to provide a supply of hot soft caps for removal from the stack one by one, each carrying binder for securing the same, and application to and molding on the container heads for holding thereon until set to securing condition.

23. In the production and application of paper material hood caps carrying a binder for securing the same on container heads by setting; those steps which consist in pro-

viding a multi-cap unit consisting of a multiplicity of paper material hood cap disks secured together in stack form by a binder set thereon and therein; then at the container hood capping situation heating said stack to approximately fuse the binder and cause distribution thereof among said disks; and separating the disks from said stack, while approximately maintaining said temperature, and applying the hot disks, each carrying its own supply of binder, to the container heads and holding the same in securing position until set thereon to securing condition.

24. In the method of producing and applying binder-carrying paper material closure disks; those steps which comprise applying binder in liquid form to a multiplicity of such paper material closure disks to supply each disk with binder and permitting the binder to set on and in a multiplicity of said disks assembled in stack form to secure the disks together for handling as a unit; subsequently reheating said unit to soften the binder and render the disks separable with each disk carrying binder for securing the same when set; and successively separating and removing the hot disks for application, from the supply of hot disks provided by said unit.

Signed at Fulton, Oswego County, New York, this 17th day of March, 1926.
